UNITED STATES PATENT OFFICE

WILHELM MÖCKEL, OF BERLIN-NEUTEMPELHOF, GERMANY

RAPID PRINTING PRESS

Application filed April 23, 1928, Serial No. 272,300, and in Germany April 30, 1927.

This invention relates to printing machines with a fixed bed and an impression cylinder which is journalled in a reciprocating carriage and is rotated in the same direction during the forward and backward motion of said carriage. The invention is characterised substantially in this, that for producing the rotary motion of the impression cylinder supporting the gripper mechanism in the same direction during the forward and back travel of the carriage, movable upper and lower racks are provided at either side of the machine, which are raised and lowered by means of cams actuated by the driving wheel 15 through intermediate gear wheels, in such a manner that the impression cylinder, in travelling over the bed during the printing stroke, engages the two lower racks and, when running idle over the bed, runs in the upper 20 racks, the printed sheet being rolled off.

From the constructional point of view, the machine has the advantage that the sheets to be printed can be piled up from the bottom to the top of the machine, that the sheets are fed over a shorter distance in a simplified manner, that the sheets are placed in position accurately and in a uniform manner, that the sheets are removed smoothly by smoothly closing grippers, that the sheets are held by 25 the grippers until the printing operation is complete and that the sheets are delivered at the front end of the machine. The machine has neither lower nor upper belts, nor cords, nor lifter bars. The ink runs in a uniform 30 manner from the ink duct over the distributing rollers to the form and the freshly printed sheets can be piled from the top of the machine to the bottom. A stationary foundation is provided, which is supported at all 35 points, and a stationary ink duct directly next to the feed table and the machine is driven from the middle.

In the accompanying drawing one constructional form of a printing machine is 40 shown by way of example,

Fig. 1 being a side elevation of the printing machine in a working position, in which the impression cylinder carriage is at one end of its travel,

Fig. 2 the other side elevation, similar to

Fig. 1, and Fig. 3 the transmission gear for driving the impression cylinder.

The machine is driven by a motor 1^a mounted in the middle of the machine, which is connected to the main driving shaft 200 for instance by a rope or belt drive 201. On the driving shaft 200 are mounted the small toothed wheels 1, the teeth of which mesh with the large toothed wheels 2 which are mounted at either side of the printing machine being fixed on a shaft 202 journalled in the side walls 16. The toothed wheels 2 are each fitted with a radially adjustable bar 3, to the unsupported outer end of which a connecting rod 4 is pivoted, the other end of which has a slot 401 in which a bush 5 mounted on a shaft 501 is adjustably fitted. The bars 3 are of triangular section slidable in V slots in the wheels 2 and are secured by bolts screwed into tapped holes 301 and bearing 60 against washers straddling the slots. On the shaft 501 at either side of the machine is mounted a large rocking wheel 6, on the lower part of which is a set of teeth 7 which meshes with the teeth of a fixed rack 8. The rotary motion of the rocking wheels 6 is transmitted by the pin 9 and the push bar 10 at either end of the impression cylinder 12 to the shaft 11 of the latter which is journalled in the side walls 15 of the impression cylinder carriage 13. Through the regular drive of the push bars 10 at either end of the impression cylinder 12 a to and fro motion of the printing carriage 13 is obtained, in which besides the impression cylinder 12 the inking mechanism 29, 30, 31 for distributing the ink is housed. By adjusting the bars 3 radially on the wheels 2 and adjusting the position of the bush 5 in the slot 401, the extent of the to and fro motion of the carriage can be regulated to the desired amount.

In order that the reversal of the motion of the carriage 13 shall be as free from shock as possible, yielding buffers 14 can be provided in the vertical outer uprights 44, 44¹ of 85 the side walls of the machine frame.

The side walls 15 of the carriage 13 are cross connected rigidly and run on the roller tracks 17 on the side walls 16 of the machine frame.

In order to ensure the carriage 13 and the impression cylinder 12 working smoothly during the printing operation, a raised portion with rollers 18 is provided on the upper edge of the side parts 15 on either side. During the printing operation the rollers 18 provide a good abutment against the upper lateral members 19 of the frame so that the impression cylinder 12 cannot give in the vertical direction. The upper lateral members 19 are strengthened by upright members 20, 21 connecting them to the side walls 16, so that the lateral members 19 cannot bend or give during the printing operation. Broad ribs are provided on either side of the bed for ensuring that the impression cylinder 12 shall roll smoothly over the bed. The circumference of the impression cylinder must correspond to twice the length of the type form, one half for the printing operation and the other flattened half for the idle return motion of the impression cylinder over the form, the latter half also housing the grippers, clamping means and elevating bars.

The rotary motion of the impression cylinder 12 is imparted to it by means of gear teeth on the cylinder which engage alternately lower and upper racks 23, 24, said gear teeth, when the cylinder is travelling over the form (forward motion), running in the two lower racks 23 provided at either side of the machine and, when the cylinder is running idle over the form, engaging in the upper racks 24. This enables the impression cylinder always to rotate in the same direction.

The raising and lowering of the racks 23 and 24 is effected by means of cams 25 which are driven through intermediate wheels by driving wheels 26 fixed on the shaft 202 of the toothed wheels 2. The racks 23, 24, are connected together at their ends by means of upright bars 90, 91 and are slidable vertically in guides (not shown) on the side members of the machine frame, said bars projecting below the lower racks and having mounted on their lower ends antifriction rollers 901, 902 which engage the cams 25, 255 which are fixed on shaft 251, 253, journalled in the side walls of the machine. Intermediately of the ends of the lower racks are fixed thereto downwardly extending bars 92 having at their lower ends antifriction rollers 903 which engage intermediate cams 254 fixed on a shaft 252 journalled in the side walls of the machine. On the shaft 251 is fixed a gear wheel 274 which meshes with a gear wheel 273 rotatably mounted on the machine frame and meshing with the wheel 26. On the shaft 252 is fixed a gear wheel 276 which is rotated by the wheel 26 through the intermediary of idler gear wheels 272, 275, the wheel 276 in turn driving a gear wheel 282 through the intermediary of idler gear wheels 277, 278, 279, 280 and 281. The setting of the cams 25, 254, 255 is such that at the commencement of the forward motion of the carriage 13, the two lower racks 23 are in their highest position and have their teeth in engagement with the rings of teeth on the printing cylinder 12. The cams have a circular portion on which the rollers 901, 902, 903 rest during the forward motion of the carriage 13, whereby the teeth on the cylinder 12 remain in engagement with the teeth of the lower racks. At the end of the forward motion of the carriage, the rollers pass on to portions of the cams, the surfaces of which are nearer the centres of rotation of the cams than the surfaces of the circular portions so that the racks 23 and 24 are lowered simultaneously so that the lower racks 23 cease to engage in the rings of teeth on the impression cylinder and the racks 24 enter into engagement with the said teeth. During the turn travel of the carriage and the impression cylinder 12 the racks 24 remain in engagement with the teeth of the cylinder which thus rotates in the same direction. During its return motion the cylinder rolls off the printed sheet while the half of the printing cylinder of reduced diameter rolls over the form. At the commencement of the next forward motion the racks 23, 24 are raised and the lower racks 23 again enter into engagement in the rings of teeth on the printing cylinder 12, the racks 24 coming out of engagement, the operation being repeated.

In the side parts 15 of the carriage 13 the three ink distributing rollers 29, 30, 31 for distributing the ink are journalled. The said distributing rollers are driven by the toothed wheel 32 (Fig. 2) rotatably mounted on the carriage and which meshes with a fixed rack 33 mounted at the side of the bed. The wheel 32 also meshes with teeth on the roller 30, which in turn drives the rollers 29, 31. The requisite axial to and fro motion of the inking cylinders is effected by a two-armed lever 34 (Fig. 1) one end of which engages in a serpentine groove in a bar 35 at the side of the bed. Of the three ink applying rollers, the two larger ones 36, 37 (Fig. 2) bear against the distributing roller 29 lying nearest to the impression cylinder 12, while the smaller roller 38 bears against the other distributing roller 30. The messenger roller 39 rests on the small upper inking cylinder 31 is journalled at either end in bearings slideable in guiding bars 41 against the action of compression springs 40 on the side facing the impression cylinder, so as to be capable of yielding within certain limits. The ink duct 42 (Fig. 2) with the ink duct roller 43 is mounted on the upright 44 of the side wall. The ink duct roller 43 is rotated by bevel wheel gearing 45 from the cam shaft 251. The ink duct roller 43 is so arranged that it moves slightly into the ink duct during the latter part of the motion of the carriage 13 so as to enable the messenger roller 39 before 130

the end of the forward motion of the carriage 13 to come into contact with the ink duct roller 43. In the continued motion of the carriage, the roller 39 is forced back in its guiding bars 41 by the roller 43 and brought out of contact with the inking cylinder 31, the springs 40 causing it to bear firmly against the ink duct roller 43. Through the latter rotating continuously, the ink is withdrawn from the ink duct. On the carriage 13 commencing its return motion, the messenger roller 39 breaks contact with the ink duct roller 43 somewhat later, after which it bears under the action of the springs 40 against the inking cylinder 31, transferring the ink which it has withdrawn to the latter.

As the impression cylinder 12 has a rotary motion but the cylinder grippers are required to grip the sheet without a jerk, the grippers must move faster than the cylinder 12 before the latter receives the fresh sheet to be printed from the feed table 66, the motion of the grippers thus being more rapid just before the sheet is received than the peripheral speed of the rotating printing cylinder. With this object in view, a cam lever 47, pivoted on the upright 44¹ and to which motion is imparted by a cam 46 on the shaft of the wheel 281 (Fig. 2), engages under the roller 48 on the gripper cam 49. The cam 46 engages a roller 461 on a rod 471 which is pivoted to the cam lever 47 and raises the roller 48 with the gripper cam 49 and lowers it again at the requisite moment to such an extent that the closing of the grippers and the commencement of the forward motion of the carriage take place at the same time. On the shaft 51 the gripper bar 52 is mounted and on the same shaft is loosely mounted the gripper cam 9. The grippers themselves are screwed to the gripper rod 53 and the levers 50 and 54 are connected rigidly to the gripper rod 53 which is movably journaled in the gripper bar 52. By the lever 54 which strikes against the fixed stop 57 the machine frame (Fig. 2) the grippers are opened at the end of the printing operation.

A suction bar 71 which is raised and lowered by means of a lever 72 rocked through the intermediary of a rod 721 by the cam 73 picks up the sheet as soon as the grippers open. The cam 73 is fixed on the connecting shaft 202 of the two large toothed wheels 2, preferably immediately at the side of the machine. The band frame 74 is connected by a system of levers and links 75, 751, 752, 753, with the cam 76 (Fig. 1) which is also mounted on the connecting shaft 202 of the two large toothed wheels 2, preferably on the opposite side of the cam 73 and thus has the requisite rotary motion imparted to it by the toothed wheels 2. When the suction bar 71 (Fig. 2) has taken hold of and slightly lifted the printed sheet, the band frame 74 is pushed under the printed

sheet which is rolled off by the printing cylinder 12. When the printed sheet rests over its entire surface on the band frame 74, the suction bar 71 again releases the sheet, whereupon the band frame 74 moves back again without the bands travelling. The rear band shaft 77 may be rigidly connected by a coupling with the toothed wheel 78 which otherwise turns loosely on it. The toothed wheel 78 meshes with a fixed rack 79. The two-armed lever 80 with a roller 80^a, which strikes against the stops 81, 82 and connects and disconnects the coupling, causes the bands to travel only when the band frame 74 is pushed under the printed sheet, for rolling at the same time another sheet towards the rear on to the delivery table.

The machine constructed as described above offers, besides the advantages already referred to, the further advantage of taking up a minimum amount of space. Thus, for instance, for a size of paper 92 x 118, corresponding to a printing form of 16 pages post

quarto, The circumference of the printing cylinder 90 is 2.00 m.

The width of the printing cylinder 1.40 m.

The length of the machine without the pile of paper 3.50 m.

The length of the machine with the pile 95 of paper 3.50 m.

The overall height of the machine 1.50 m.

The width of the machine 2.20 m.

What I claim is:

1. A printing machine having a stationary type bed, an impression cylinder capable of rolling over the said bed, a carriage in which the impression cylinder is journaled, means for imparting a forward and backward motion to the carriage and cylinder and means for imparting a rotary motion to the cylinder in the same direction both during the forward and backward motion of the cylinder, the said latter means comprising a ring of teeth on the cylinder, a movable upper rack 100 and a movable lower rack and means for moving the lower rack into engagement with the said ring of teeth during the forward operative motion of the cylinder and for moving the upper rack into engagement with the said ring of teeth during the backward idle motion of the cylinder and delivery of the printed sheet, as and for the purpose set forth.

2. A printing machine having a stationary type bed, an impression cylinder capable of rolling over the said bed, a carriage in which the impression cylinder is journaled, means for imparting a forward and backward motion to the carriage and cylinder and means for imparting a rotary motion to the cylinder in the same direction both during the forward and backward motion of the cylinder, the said latter means comprising a ring of teeth on the cylinder, an upper and a lower rack and means comprising a driving wheel, toothed 125

wheels, a train of intermediate wheels and a cam for bringing the lower rack into engagement with the said ring of teeth during the forward operative motion of the cylinder and for bringing the upper rack into engagement with the said ring of teeth during the backward idle motion of the cylinder and delivery of the printed sheet, as and for the purpose set forth.

In testimony whereof I have signed my name to this specification.

WILHELM MÖCKEL.
